Primary Examiner—Kay H. Chin

[57] CLAIM

The ornamental design for a aircraft, as shown and described.

DESCRIPTION

FIG. 1 is a front elevational view of an aircraft showing my new design;

FIG. 2 is a front elevational view thereof in parked condition;

FIG. 3 is a side elevational view of FIG. 1, the opposite side view being a mirror image of that shown;

FIG. 4 is a side elevational view of FIG. 2;

FIG. 5 is a top plan view thereof;

FIG. 6 is a bottom plan view thereof;

FIG. 7 is a side elevational view thereof in climb-out condition;

FIG. 8 is a top perspective view thereof; and,

FIG. 9 is a bottom perspective view thereof.
